WILLIAM H. SINCLAIR, OF BERKELEY, CALIFORNIA, ASSIGNOR TO MANIFOLD IMPRESSIONS CORPORATION, OF CARSON CITY, NEVADA, A CORPORATION OF NEVADA.

INTERMITTENT PRESSURE MECHANISM FOR TYPE-IMPRESSION DEVICES.

Application filed August 28, 1926. Serial No. 132,070.

My invention relates generally to type-impression devices and especially to machines employing a platen and type-impact bars, each of the latter carrying plural characters individually distinguishable, and which are termed "upper case" and "lower case". These terms refer in a special sense to "capitals" and "small" letters respectively; and while, it is true, such classification comprises the greater number of type used, many bars carry plural type-characters not necessarily falling strictly within said terms. For the sake of simplicity, however, I shall herein use these terms as indicative of relative positions on the bars, without regard to the nature of the characters occupying such positions.

Typewriters may be taken as illustrative herein of the class of type-impression devices with which my invention is especially concerned. In some of these machines, a vertical movement of the platen is provided to selectively change the printing line on the "work" as I shall herein term the sheet or sheets passing through the machine, in order to present said line to the point of type impact of one or the other of the plural characters on the type-bar; and in other machines the necessary variation is made by a vertical movement bodily of the type-bar basket. There are other expedients for this purpose, but the above noted are sufficient to illustrate the difficulty which it is the object of my invention to avoid.

This difficulty is the objectionable feature of the simultaneous impact of both upper and lower case type, one in full and the other in part impression, resulting in a perfect line of printed characters on the work and a blurred, more or less indistinct line parallel with the first line, which is confusing and at best is unsightly and lacking in neatness.

The essential reason for this undesirable result is the imperfect flattening of the work in the printing line; and though a presser bar or paper finger or guides are usually associated with the platen to hold said work as close as possible, these are necessarily relatively remotely located from the printing line on either side thereof, so that the work may slightly bulge at or in the vicinity of said line and thus receive the simultaneous impressions, one complete and the other faulty, of both upper and lower case type.

This is the case even when single record sheets comprise the work, and may be due to wear and tear or faulty adjustment or manipulation; but when manifolding is in progress and the work comprises a plurality of individuals, both record and transfer sheets or members, it is obvious that the resulting thickness can only accentuate the failure of close contact or flatness and the consequent bulging.

While the difficulty under consideration is thus seen even in ordinary machines, and in the customary work thereof, I have still to point out a problem inherent in the use and operation of a special type of machine, and in the solution of which my invention may be said to reach its highest development and utility.

I refer to those manifolding typewriters in which one or more manifolding members lie between the record sheets and have an oscillating or other movement imparted to them independently of the record sheets, for the purpose of causing their entire surface to be used in transferring function. In such work assemblages, freedom for the independent movements of said manifolding members is essential, and even the customary presser bars or fingers are restrictive of this freedom. To retain this necessary freedom and yet provide for a close or flattened contact of the composite work with the platen is possible with my invention, as will hereinafter appear.

Briefly stated and in its broadest aspect my invention comprises means for flattening the work in the printing line in the immediate vicinity of the point of type impact just prior to impact, and immediately thereafter relieving said pressure.

In its best form said means are automatic in operation, and, in practice are made dependent upon the key-actuation of the type-bar. Furthermore in its most acceptable form said means are associated either as integral with or as carried by the vertically reciprocating ribbon-jumper of the center guide, which alternately presents and withdraws the ribbon to and from the line of type impact.

The nature of my invention in its preferred form will now be fully described by reference to the accompanying drawings, it being understood that changes may be made

within the scope of the claims hereunto appended, without departing from the spirit of the invention.

Fig. 1 is a front view, chiefly diagrammatic, and indicating such parts of a typical typewriter as are required for reference in describing my invention.

Fig. 2 is a fragmentary face view of a printed sheet of the "work" showing the complete impression of the upper case type and the underlying impression of a part of the lower case type, an effect which, as above stated, it is the object of my invention to obviate.

Fig. 3 is a side view of the upper end of a type-bar indicating the upper and lower case type carried thereby.

Fig. 4 is a front elevation of the usual center-guide, showing the reciprocative ribbon-jumper (through which the ribbon is threaded in its depressed position, which provides, as is customary, for making the impressions visible).

Fig. 5 is a view similar to Fig. 4 but showing the ribbon-jumper elevated to the printing line just prior to type impact.

Fig. 6 is a sectional detail, showing the ribbon-jumper depressed, and, indicating the relation, to the platen, of my intermittent pressure member carried by said jumper.

Fig. 7 is a rear elevation, enlarged, of my intermittent pressure member.

Fig. 8 is a perspective view, from the rear, of the improved intermittent pressure mechanism comprising the assembled center-guide, ribbon-jumper and pressure member.

Fig. 9 is a diagrammatic sectional detail showing the relation of the platen, the "work", and the pressure member, when the pressure is relieved, and indicating the necessary freedom in such relation.

Fig. 10 is a diagrammatic detail showing the relation of the parts of Fig. 9, when said pressure member is active.

Referring to Fig. 1, the numeral 1 indicates the frame of a typewriter, 2 the cylindrical platen, 3 the paper-table, 4 the type-bar basket, 5 one of the type-bars, 6 the center-guide, 7 the ribbon-jumper carried by said center guide, 8 the ribbon threaded through the jumper and 8' the ribbon spools.

As indicated in Fig. 3, the free end of the type-bar 5 carries plural type in alignment longitudinally of the bar, the outermost, represented by 9 being usually "upper case" and the inner one, 10, being "lower case", as for example, capitals in the first instance and small letters in the second instance, or any other different characters usually employed and positioned in alignment.

For several reasons, and under a variety of circumstances, it not infrequently happens that when the shift is made to print

from either "case" type, a portion of the other "case" type also reaches the work, resulting in an unsightly blurring. This is shown in Fig. 2 in which 11 indicates the "work" or sheet to be printed upon, the upper case type impressions 9' being perfect, and the lower case type impressions 10' incomplete.

It is common practise in typewriters to carry the ribbon to the printing line immediately before the type impact, and to withdraw it immediately after said impact so that the impression becomes visible. This is the function of the ribbon-jumper 7 through which the ribbon is threaded, and is illustrated in Figs. 4 and 5. The center guide 6 is a fixed plate and the ribbon-jumper 7 is mounted for linear reciprocation upon said guide.

I have not deemed it necessary to show the transmitting connections by which the movement of the ribbon-jumper is effected by suitable association with the operating keys of the machine. It is sufficient to indicate by the lever 12 of Fig. 8 the terminal member of said connections.

In Fig. 4 the depressed position of the ribbon-jumper relatively to the printing line, indicated by the row of numerals, shows the reason for the withdrawal of the ribbon namely, to make them visible. In Fig. 5 the elevation of the ribbon-jumper shows the covering of the printing line by the ribbon, in order to receive the type impact.

Thus far the description and illustration have been directed to common practice, and I deem it advisable, before proceeding to specifically disclose my improvement, to point out the problems involved in this common practice, which it is the object of my invention to solve.

Manifestly the absolute flattening out of the work against the platen, in the printing line, is the theoretical condition for perfect impression. Any bulging or looseness of the work is destructive of such impression. Paper guides in a variety of forms and positions are used to hold the work as flat as possible upon the platen, and these have been located as near as may be, above or below, to the printing line, but not in said line since such position would interfere with visible writing in that they would cover up the impressions previously made in the line. Therefore, even where the work consists of a single sheet, it may and often does happen that there will be a looseness or lack of flatness in the sheet in the line of type impact, a slight bulge in fact, sufficient in extent to cause a portion of the lower case type to impress it, in addition to the desired impression of the upper case.

This undesirable result is all the more likely to happen if the work comprises a plu-

rality of sheets, as for example in manifolding, for in that case the thickness of the work and its composition as separate units renders it quite likely at the printing line 5 to be loose both inherently and with relation to the platen.

While, even in the ordinary work and with the common types of machines as I have just explained, there is a necessity for 10 means for intermittently holding the work flat in the printing line and in the immediate vicinity of the point of type impact, and at the time of the impact, and of withdrawing such means to render the writing visible, 15 such necessity is present with greater insistence in those forms of machines especially adapted for manifolding in which the manifolding members lying between the paper sheets have movements imparted to them 20 which are independent of said sheets, as for example, a travel of said members or an oscillation either longitudinal or transverse or both, to provide for utilizing substantially their entire surface area. In such machines 25 the relief from pressure at the time of said independent movement of the manifolding members is imperative, in order to provide sufficient freedom or looseness between the work components to enable said movements 30 to be made without undue friction or blurring tendency. All the terms of these problems are solvable in practice by the simple but effective expedient of carrying the intermittent pressure means upon the reciprocative 35 ribbon-jumper.

Referring now to Figs. 7 and 8, and particularly the latter, 13 is the pressure device or member. It consists of a pair of spaced members on the rear face of the ribbon-jumper 7, one on each side of and in the line of the opening 7' of said jumper through which the type strikes. In the form shown 40 these members are strips secured to the ribbon jumper, and are yielding ones, due to 45 having resilient head bends 13'.

The relation of the improved jumper assembly to the platen is shown in Fig. 6; and the effect of the pressure member 13 is well illustrated in Figs. 9 and 10.

In Fig. 9 the pressure member 13 is shown 50 in its retracted or withdrawn position, wherein it is clear of the work 11 and the latter is shown as capable of presenting its written line to view, and as having a freedom 55 from pressure sufficient for the movements of any of its components.

In Fig. 10 the pressure member 13 has moved up and into contact with the work, and has pressed it flat against the platen 60 ready to receive the type impact.

The operation, briefly, may now be stated. The normal position of the ribbon-jumper and ribbon is down, so that the printing line 65 on the work is in sight. As a key is pressed and the type bar begins to rise, the ribbon-

jumper also rises and carries the ribbon to and in front of the printing line, and also carries the pressure strips 13 into contact with the work, thereby flattening the latter against the platen immediately on each side 70 of the point of type impact. This position and effect take place a moment prior to the type impact, and, since the work is then pressed and held flat, it receives a perfect impression of the character intended to be 75 printed without any additional impression of another character or any portion thereof. As the key is relieved and the type bar swings away, the ribbon-jumper and ribbon move down, thereby uncovering the printing 80 line for visibility, and also carrying the pressure strips 13 away from contact with the work, so that the latter is free enough to permit the independent movements of any 85 manifolding members which may be in use.

Although I have hereinbefore, in referring to the blurring of the work, somewhat briefly mentioned its causes, I deem it well to point out other considerations having direct bearing upon the utility of my invention in obviating the undesirable result of causes inherent in the problem, and which are either in addition to or aggravate the immediate cause, namely the imperfect relation of the work to the impact surface of the 90 platen, as manifest in the bulging of the work. This is especially pertinent to platens as ordinarily employed with loose sheets of carbon paper.

The type carried on the ends of the bars 100 are manufactured with a certain arc or curve extending from the limits of the upper to the lower case.

This arc or curve is a previously determined one, and is designed to coordinate 105 with the imaginary arc or curve of the rubber sheath forming the periphery of the platen.

When this rubber sheath is newly made of 110 fresh rubber, it is ground to a certain diameter to correspond in arc to the curve on the face of the type characters whose impact it is designed to receive in true relationship. The arc of the type remains a constant in theory, due to the nature of the material 115 composing it, assuming normal operative pressure and continuity of clean type. However, as hereinafter pointed out, this arc also becomes a variable. The character of the material composing the sheath is such 120 that both the wear upon it and the chemical action which effects it from vulcanization etc., make it a variable in diameter, and consequently in arc. Thus there is the problem of accommodating or adjusting the position 125 of the record sheets and copying medium between a constant arc and a variable arc, or more correctly stated, adjusting record sheets and copying medium between two variable arcs of contact with said record sheets 130

and copying medium; so as to avoid blurring. It is obvious that some supplemental agency must become operative or the results will not be uniform, and as the changes occur, the result must otherwise be distorted. Such is the case. Even if perfect adjustment or accommodation is made in a new typewriter, as the platen recedes in diameter, the blurring gradually begins to take place, and is manifested in a line below or above the typed one, as though it were a continuous series of merged dots. This line is really formed by the tips of the other case of letters or characters, resulting from the distorted position of the "work" due to the changed diameter of the platen.

It will be apparent that this condition is gradual and that the remedy for this changing condition, must be automatic in character. My invention is thus automatic and prevents the "work" from bulging or assuming a distorted position with relation to the other case type than the one intended to be employed, arising from changing platen diameter. While it may be possible to bend the type to properly correspond to the changing diameter of the platen, this invention does away with that necessity.

The next point to be mentioned in this connection, is the fact that my invention automatically corrects the blurring arising from distortion of the arc of the type due to undue pressure from improper pounding of the keys, as well as the normal wear on the type. This, it will be noted increases the degree of the arc on the outside of the "work", instead of decreasing it underneath the work.

Still another very common and frequent cause of this blurring line previously referred to, is the failure of the stenographer to clean the type, that is to keep them clean. The result of this failure is that both dirt and ink, and lint from the original copy ribbon accumulate on the face of the type. This added thickness changes the true theoretical coordination of the arcs of the type and platen, because it will be quite plain that this added thickness is not uniform on all the type or characters taken collectively relatively. An analysis of the result is that there is first a constantly changing individual arc on the outside of the "work", that is, the record sheets and copying medium, as well as underneath the same. The paper guides on the machines of today merely serve to conform the "work" to the general contour of the platen. My invention has a special object as a paper guide in conforming the "work" to variations in the arc of the platen with those of each individual type, in a manner to avoid blurring on the work. Second, and more important, the accretions on the type lengthen the contact length of the arc, and tend to partially close up the

opening between the type characters, thus exaggerating the tendency to the blurring contact which the exactly calculated theoretical opening was measured to avoid if the type were clean.

70

It will now be seen from the problem herein and the disclosure of a practical means for solving it, that all the elements necessary to a solution are known and successively considered.

For example, the type bar with the type located at one extremity thereof, forms a lever with a striking head.

It is so constructed because the nature of the result sought is a violent one, that is, one characterized by great physical force, the object being to impress or imprint.

The elements necessary for the objects of this invention are such as to produce the reverse of this result.

While the action of the mechanism must be swift in approach and recession, the actual contact resulting must be so gentle in action and motion as to result

in a degree of impingement less than impact.

The nature of the mechanism, while operating in timely relation to the swift movement of the type, must be of a form and movement to mitigate what would otherwise become an impact.

The movement must be gentle in action and motion; the contact must be soft and easily yielding to pressure, although swift; somewhat in the nature of a wiping contact.

If the form of the contact member were not such that the contact was distributed over a sufficient contact area, it

would be either a very difficult or impossible problem to supply the elements of motion which would avoid the very result the invention is intended to eliminate.

In other words, if the contact member were concentrated to a point, it would tremendously increase the requirements for the elements of motion necessary to avoid an imprint.

This invention is of such a form, and the movements of such a character as to form a combination capable of attaining the results necessary to meet all the terms of the problem.

I claim:

1. In a type impression machine and in combination with its reciprocative ribbon-jumper adapted to carry the printing ribbon to and from the printing line of the work in the machine, a member reciprocating in unison with said ribbon-jumper adapted to impose flattening pressure upon and relieving said work in the printing line in timely accord with the impending and completed type impact, respectively.

2. In a type impression machine and in combination with its reciprocative ribbon-jumper adapted to carry the printing ribbon to and from the printing line of the work in the machine, a member reciprocating in unison with said ribbon-jumper and positioned relatively thereto adapting it to impose flattening pressure upon and relieving

- said work in the printing line adjacent the point of type-impact in timely accord with the impending and completed type impact, respectively.
5. 3. In a type impression machine and in combination with its reciprocative ribbon-jumper adapted to carry the printing ribbon to and from the printing line of the work in the machine, a member carried by
10. said ribbon-jumper in position adapting it to impose and relieve flattening pressure upon the work in the printing line in timely accord with the impending and completed type impact.
15. 4. In a type impression machine and in combination with its reciprocative ribbon-jumper adapted to carry the printing ribbon to and from the printing line of the work in the machine, a resilient member carried by
20. said ribbon-jumper in position adapting it to impose and relieve a yielding flattening pressure upon the work, in the printing line, in timely accord with the impending and completed type impact.
25. 5. In a type impression machine and in combination with its reciprocative ribbon-jumper adapted to carry the printing ribbon to and from the printing line of the work in the machine, a strip on the inner face of
30. said jumper adapted to impose intermittent pressure upon said work in the printing line in timely accord with the impending and completed type impact.
6. In a type impression machine and in combination with its reciprocative ribbon-jumper adapted to carry the printing ribbon to and from the printing line of the work in the machine, a strip on the inner face of the said jumper, said strip having a resilient end adapted to impose intermittent pressure upon said work in the printing line in timely accord with the impending and completed type impact.
7. In a type impression machine and in combination with its reciprocative ribbon-jumper adapted to carry the printing ribbon to and from the printing line of the work in the machine, a pair of spaced strips on the inner face of said jumper, adapted to impose intermittent pressure upon the work in the printing line on each side of the point of type impact, and in timely accord with the impending and completed type impact.
8. In a type impression machine and in combination with its reciprocative ribbon-jumper adapted to carry the printing ribbon to and from the printing line of the work in the machine, a pair of spaced strips on the inner face of said jumper, said strips having a resilient end adapted to impose intermittent pressure upon the work in the printing line on each side of the point of type impact, and in timely accord with the impending and completed type impact.
- In testimony whereof I have signed my name to this specification.

WILLIAM H. SINCLAIR.
